CLAIM

We claim the ornamental design for a diamond automotive grille, as shown and described.

DESCRIPTION

FIG. 1 is a front view of the diamond automotive grille. FIG. 2 is a rear view of the diamond automotive grille. FIG. 3 is a left side view of the diamond automotive grille. FIG. 4 is a right side view of the diamond automotive grille. FIG. 5 is a top view of the diamond automotive grille; and, FIG. 6 is a bottom view of the diamond automotive grille. The diamond automotive grille of the invention is characterized by diagonally aligned apertures approximately $\frac{1}{2}$ inch in width. The broken lines are shown for illustrative purposes only and form no part of the claimed design.
